UNITED STATES PATENT OFFICE

NAT L. SOLOMON, OF BROOKLYN, NEW YORK

DESIGN FOR A HAIR NET

Application filed November 21, 1930. Serial No. 37,752. Term of patent 14 years.

To all whom it may concern:

Be it known that I, NAT L. SOLOMON, a citizen of the United States, residing at Brooklyn, New York, have invented a new, original, and ornamental Design for Hair Net, of which the following is a specification, reference being had to the accompanying drawing, forming part thereof, wherein the figure is a side elevational view of the hair-net showing the new design.

I claim:

The ornamental design for a hair net as shown.

NAT L. SOLOMON.
